UNITED STATES PATENT OFFICE.

EMIL TYDEN, OF CHICAGO, ILLINOIS, ASSIGNOR TO THE METROPOLITAN FILTER COMPANY, OF SAME PLACE.

WATER-FILTER.

SPECIFICATION forming part of Letters Patent No. 602,883, dated April 26, 1898.

Application filed June 21, 1897. Serial No. 641,610. (No model.)

To all whom it may concern:

Be it known that I, EMIL TYDEN, a citizen of the United States, residing at Chicago, county of Cook, and State of Illinois, have 5 invented certain new and useful Improvements in Water-Filters, which are fully set forth in the following specification, reference being had to the accompanying drawings, forming a part thereof.

10 In the drawings, Figure 1 is a front elevation of my improved filter. Fig. 2 is a vertical section axial with respect to the two cylinders and connecting-duct. Fig. 3 is a plan of the base-fitting on which the cylinders are 15 mounted. Fig. 4 is a horizontal section at the line 4 4 on Fig. 2. Fig. 5 shows the filter mounted by connection with a water-supply pipe.

A is a cast fitting constituting the base of 20 my filter. It is provided with pipe connections A^a and A^b, the former for attachment to the water-supply pipe and the latter to afford connection for a discharge-faucet. On the upper side it has two circular flanges 25 A^c and A^d, interiorly threaded and adapted to receive the water-cylinders O and Q, respectively. In the base A are formed two 30 cavities P and S, which open inwardly and thereby communicate with the lower ends of the cylinders O and Q, respectively. Concentric with the flange A^c, into which the cylinder O is screwed, is an annulus A^e, seated with intervening packing a^e on the base A and having a flange A^f, within which the filtering-cylinder H is retained, being stepped 35 on a packing-gasket O^a, lodged upon the upper surface of the web of the fitting A, said annulus A^e operating practically as if it were a flange or uprise from the base A, and within this annulus A^e is a third annulus, which is 40 a flange or boss around the margin of the opening P^a into the chamber P, and into this flange or boss A^f there is screwed a pipe G.

V is a cap whose marginal flange V^a receives 45 the upper end of the filtering-cylinder H, a packing-gasket O^b being interposed between the end of the cylinder H and its seat on the cap. Centrally disposed with respect to the cap, depending from its under side, is 50 a hollow hub V^b, which at its lower end is threaded, and thereby adapted to be screwed

onto the upper end of the pipe G, and at the center of the cap it has an aperture V^c. In the upper web of the fitting A, inside the flange A^c, is an opening K^a, leading by way 55 of the passage K to the chamber S, and at this opening K^a there is connected a pipe I, opening between the pipe G and the filtering-cylinder H. Outside of the annular flange A^e, in the upper web of the fitting A, is an 60 opening R^a, which leads by way of the passage R to the faucet connection A^b. Between the flanges A^c and A^d a passage T opens into the cylinder O, said passage being extended vertically through the fitting A without direct communication with any other of the 65 passages in said fitting, and at the lower end of said passage T is connected a petcock E. Considering the structure thus described, it will be noticed that when the filter is attached 70 to the water-supply pipe the water entering at A^a may pass through the chamber P up through the pipe G, and thence through the aperture V^c in the cap V it may pass into the annular chamber W between the cylinder O 75 and the filtering-cylinder H, and from said chamber W it may pass by way of the passage R through the discharge-cock D, or said discharge-cock being closed it will pass through the wall of the filtering-cylinder H and occupy 80 the annular chamber F within said filtering-cylinder and outside the pipe G and may be drawn from the chamber F by the petcock E, or it may pass also by way of overflow out of the top of said chamber F, following through 85 the pipe I and passage K into the chamber S, and thence up into the reservoir or storage-cylinder Q. The entrance to the reservoir Q is controlled by a valve L, seating upwardly on the bottom Q^a, which is sprung upward 90 from the horizontal web of the fitting to form a valve-chamber under said bottom. A turret Q^b is provided at the center of the bottom to afford guidance for the stem L^a of the valve L, and to this stem is connected a float N by 95 means of a chain M, the length of which permits the float to rise nearly to the top of the cylinder Q, and when at its limit to hold the valve L seated upwardly.

L^b is a cup which receives the chain and 100 affords lodgment for the float N when the latter is at the lowest point. In the chamber

which is formed in the hollow hub V^b of the cap V there is a valve U , adapted to seat over the upper end of the pipe G —that is, at the lower end of the chamber in the hub V^b . 5 This valve has a stem U^a , which extends out through the opening V^c in the cap and is suitably guided in a yoke or staple V^d , which springs from the top of the cap and overhangs the opening V^c for the purpose of affording 10 guidance to the valve-stem. The other end of the stem below the valve U is bent at U^b , so that it obtains guidance in the pipe G . The purpose of this valve is that if the water should be drawn from the supply system at 15 some point lower than that at which the filter is attached, the outlet thus opened being sufficient to exhaust the entire supply, whereby the flow at such lower opening would tend to draw the water out of the filter, the reverse 20 movement of the water thus induced operating upon the valve U will seat it downward over the end of the pipe G and cause it to retain the water in the filter. The stem U^a of the valve is of such length that its upper 25 end is stopped against the cap V when the valve U is at a position which permits the water to flow around it and out through the aperture V^c .

In the use of this filter water for drinking 30 or any other purpose for which the filtered water is desired will be drawn through the petcock E . This petcock, taking the water from the lowest point of the annular chamber F inside the filtering-cylinder H , will draw the 35 coldest water and that which was last filtered, because the chamber F becoming filled to the top of the pipe I the overflow will constantly pass over into the reservoir Q , and water is carried from the reservoir only by the same 40 passage—that is, by passing back through the overflow-pipe I into the annular chamber F and out through the petcock. Water for other use not requiring it to be filtered is drawn through the cock D , and such water being in 45 domestic use always drawn in much larger quantity than that which is filtered there will be a constant cooling effect experienced by reason of such water passing all around the filtering-cylinder H in comparatively large 50 quantity, tending thus to cool the water which may have been standing some time in the chamber F , so that the water drawn through the petcock E , flowing during the time the cock is open at a greater rate than it can permeate the filter, will tend to create a vacancy 55 in the upper part of the chamber F , which will be filled by the return of the water from the reservoir through the pipe I ; but before this water thus returned from the reservoir reaches 60 the bottom of the chamber F , so as to be ready to pass out through the petcock, it will be exposed for a considerable time to the cooling effect of the frequently-changed water in the outer space F around the filtering-cylinder 65 H , which, entering directly from the supply pipe, may be presumed to be colder than that which has been standing for some time in the

reservoir Q . In practice in domestic use when the supply water is reasonably cool the filtered water drawn through the cock E will at 70 all times be nearly as cool as if it were drawn directly from the supply-pipe, and at the same time the supply maintained in the reservoir Q makes it possible to draw rapidly from the petcock without emptying the chamber F , because the latter is constantly supplied from the reservoir, the reservoir being refilled by filtering in the intervals between drawings from the petcock. The supply drawn from the cock D , being compelled to pass through the 80 narrow cylindrical passage between the filtering-cylinder H and the outer case O and the size of the faucet being such as to permit it to flow freely, will operate to scour the outer 85 surface of the filtering-cylinder and carry off the deposit due to filtering.

In Fig. 5 there is shown a T D^a , interposed between the cock D and the filter for the purpose of connecting the pipe D^b , which may extend to any other part of the house where 90 water may be drawn, as to a bath-room, so that not only the water drawn at the faucet D , but all the water drawn at any point in the house, may pass around the cylinder H and assist in keeping it cold. 95

I claim—

1. In combination with a filter, a reservoir connected with the filtered-water chamber of the filter adapted to receive filtered water from the latter and to deliver the same back 100 thereinto, and a cock for drawing water from the filtered-water chamber.
2. In a filter, in combination with a filtered-water chamber having a cock for drawing water therefrom at the bottom; a reservoir 105 communicating with the filtered-water chamber at the top of the latter, whereby the filtered water from said chamber overflows into the reservoir and returns by the same passage when the water is drawn from the bottom of 110 the chamber.
3. In a filter, in combination with the water-inlet pipe, a check-valve adapted to be seated by backflow through said pipe to prevent the emptying of the filter as described. 115
4. In a filter, in combination with the central supply-pipe G , the filtering-cylinder H outside the same and the outer cylinder O , whereby there are formed two annular chambers F and W located respectively between the inner pipe and the filtering-cylinder and between the filtering-cylinder and the outer cylinder; the cap V which closes the chamber F at the top having a waterway through it leading from the pipe G to the outer chamber 120 W , and a faucet leading from the lower end of said outer chamber W , whereby the drawing of water from said faucet scours the outer 125 surface of the filtering-cylinder.
5. In a filter, in combination with the water-inlet pipe, the filtering-cylinder and the outer cylinder, the cap which closes the upper end of the chamber between the inlet-pipe and the filtering-cylinder and which has a central 130

waterway affording communication from the pipe to the space outside the filtering-cylinder; a reservoir communicating with the upper part of the space inside the filtering-cylinder and having no communication with the space outside the same; a drain-cock leading from the lower part of the space inside the filtering-cylinder, and a faucet leading from the lower part of the space outside the cylinder, all combined and operating for the purpose set forth.

6. In a filter, in combination with the central inlet-pipe G, filtering-cylinder H and outer cylinder O and their respecting intervening chambers F and W; the cap V which closes the upper end of the chamber F, said cap having a hollow hub constituting a valve-chamber having a lower support and con-

nected at said support to the upper end of the pipe, said chamber having an upper port 20 through the cap, and the valve U lodged in said chamber and adapted to seat downwardly at the lower port thereof, and having its stem extending up through the upper port, and the cap B of the outer cylinder arranged to stop 25 the end of the stem when the valve U is intermediate the upper and lower ports of the valve-chamber.

In testimony whereof I have hereunto set my hand, in the presence of two witnesses, at 30 Chicago, Illinois, this 17th day of June, 1897.

EMIL TYDEN.
